VAULTER'S LANDING CUSHION

Thomas O. Olsen, 910 S. Santa Fe, Salina, Kans. 67401

Filed Jan. 25, 1966, Ser. No. 761

Term of patent 14 years

(Cl. D34—5)

Fig.1.

Fig.2.

Fig.3.

Fig.4.

FIG. 1 is a front perspective view of a vaulter's landing cushion, showing my new design.

FIG. 2 is a front elevational view.

FIG. 3 is a rear elevational view; and

FIG. 4 is a side elevational view.

I claim:

The ornamental design for a vaulter's landing cushion, as shown.
